UNITED STATES PATENT OFFICE.

WILLIAM H. HARRIS, OF RICHMOND, VIRGINIA.

DESIGN FOR A BADGE.

Application filed October 2, 1926. Serial No. 19,221. Term of patent 3½ years.

To all whom it may concern:

Be it known that I, WILLIAM H. HARRIS, a citizen of the United States, residing at Richmond, in the county of Henrico and State of Virginia, have invented a new, original, and ornamental Design for a Badge, as shown in the accompanying drawing, and described in the following specification.

The figure is a perspective view of a badge, showing my new design.

I claim:

The ornamental design for a badge, as shown.

WILLIAM H. HARRIS.
